UNITED STATES PATENT OFFICE.

RICHARD W. HEARD AND RICHARD A. L. SNYDER, OF SWISSVALE,
PENNSYLVANIA.

SUBDIVIDING LAMINATED MATERIAL.

SPECIFICATION forming part of Letters Patent No. 621,410, dated March 21, 1899.

Application filed September 23, 1897. Serial No. 652,689. (No model.)

To all whom it may concern:

Be it known that we, RICHARD W. HEARD and RICHARD A. L. SNYDER, citizens of the United States, residing at Swissvale, in the county of Allegheny and State of Pennsylvania, have invented or discovered certain new and useful Improvements in Subdividing Laminated Material, of which improvements the following is a specification.

10 The invention described herein relates to certain improvements in the separation of laminæ of mica and other similar materials, and the invention is hereinafter more fully described and claimed.

15 In the accompanying drawings, forming a part of this specification, Figure 1 is a top plan view of our improved separating-machine. Fig. 2 is a side elevation of the same. Fig. 3 is a sectional elevation, the plane of section being indicated by the line III III, Fig. 1. Fig. 4 is a top plan view, on an enlarged scale, of a portion of the machine. Fig. 5 is a sectional elevation, the plane of section being indicated by the line V V, Fig. 1. Fig. 25 6 is a sectional detail view of the mica-holding devices, and Fig. 7 is a sectional detail view of a portion of the separating-blade and the table.

In the practice of our invention we employ 30 a blade of suitable edge contour and a holder for the mica, one of said parts being movable so as to cause the blade to enter between adjacent laminæ. In the form of apparatus shown the blade 1 is secured upon a vertical shaft 2, mounted in suitable bearings, so that 35 its upper end will project above the surface of the table 3 and move the knife along parallel and in close proximity therewith. As clearly shown in Fig. 1, this revolving knife 40 1 is provided with a projecting horn *a*, approximately V-shaped in cross-section. The blade is made as thin as compatible with a certain amount of rigidity, and its entering point is slightly beveled on both sides. The 45 amount of bevel on the under side of the point of the blade will be entirely dependent upon the thickness of laminæ which it is desired to separate from the block—that is to say, the thicker the laminæ to be separated the greater 50 the bevel given to the under side of the blade.

The blade is held against the surface of the table adjacent to the mechanism employed for holding the mica by a roller 4, mounted on a pivotally-mounted arm 5, and is held against the blade by a spring 6. In order to 55 hold outer portions of the block of mica in position, we employ a brush 7, which is secured to arms 8, pivotally mounted upon standards on the frame 9, and the brush is held in contact with the block of mica by 60 means of springs 10^a. This brush bears, as clearly shown, upon the block of mica near the edge at which the separating-knife enters. The rear portion of the block is held in position upon the table by means of a presser-foot 65 10, secured to rods 11, passing up through the frame 9. Yielding pressure is exerted upon the presser-foot by springs 12, surrounding the supporting-rods. Any suitable means may be employed for holding the block from movement along the table with the blade—such, for example, as that shown, and consisting of pins 13, mounted in suitable guide-sockets 14 on the frame 9. These pins are held down in operative position by the springs 15, having one 70 end connected to the frame 9, while the opposite end is connected to a cross-bar 16, attached to the upper ends of the pins 13. In order to lift these pins, so as to permit the passage of the separating-blade and the lamina 75 separated from the block, rollers 17 are loosely mounted in yokes 18, secured to the pins 13. As clearly shown in Fig. 5, these rollers are mounted at an angle to the surface of the table and are arranged at such a distance apart 80 as to permit of the passage of the front end of the blade between them and the table without effecting any vertical movement of the rollers or pins; but they will be raised, together with the pins, as the shoulders *b* of the 85 blade come in contact therewith. Adjacent to the holding mechanism just described an opening is formed through the bed of the table to permit of the sheet or lamina separated from the block to drop away from the blade 90 onto an endless apron 19, mounted on pulleys 20, arranged on opposite sides of the machine. One of these pulleys is positively driven by a belt 21, which passes around a suitable pulley 95 on the knife-shaft 2. On this shaft is also 100

mounted a pulley 22, around which is passed a belt 23, which serves to drive a brush 24, arranged on the opening in the table and designed to detach any sheet of mica or dust which may adhere to the under side of the blade.

As it is desirable to prevent the movement of any portion of the block of mica before at least the front end of the blade has passed entirely through the same and as it is also desirable to insure the movement of a detached sheet with the blade from under the block, grooves 25 are formed in the surface of the table to permit of the projection of the pins 13 below the surface of the block and for the reception of projecting lugs 26, formed on the under side of the blade. The sheets of mica separated from the block and carried along with the blade by the lugs 26 are very thin and occasionally adhere so closely to the under side of the blade that the brush 24 will not dislodge them. In order to overcome such adherence and to insure the dislodgment of the sheets, springs 26^a are attached to the under side of the blade in front of the lugs 26, as shown in Figs. 1 and 7. The ends of the springs are made thin and lie in close contact with the under side of the blades, so as to pass freely over the separated sheets, but the middle portion is bowed, so as to force the sheets away from the blade. As it is desirable that portions of the holding-pins 13 should always project a little below the under surface of the block, grooves 28 are formed in the upper surface of the blade 1, and the lifting-rollers are so adjusted on said pins as to lift the pins only a sufficient height to permit of their entrance into the grooves and not above the upper surface of the blade. For many purposes the laminæ separated should be as thin as possible, and as it is practically impossible to so form the bevel at the front point of the knife as to effect the separation of a lamina as thin as desired we effect initial separation of the block of mica into sheets at one edge of a block. While this separation can be effected in many ways, we prefer to do it by grinding the edge of the block and have found that in such grinding operation the laminæ are opened up and separated by the grinding along their edges, and the material abraded from the edges of the separated laminæ is forced or wedged in between the same, thereby holding them in open position ready for the operation of the splitting-knife. This method effects the subdivision of the block into thinner sheets than is possible by any of the methods now in use and holds the sheets separated at their edges for the entrance of the blade. After the edge of the block has been ground or the initial separation effected the block is placed in the holding device with the opened edge toward the knife, which is then rotated. The point enters between adjacent laminæ, and the diverging edges thereof act as a wedge to separate one lamina in all directions from the one

next adjacent. After passing through the block the point of the blade passes underneath the rollers, and thereby lifts the holding-pins, 70 so as to permit of the passage of the knife under them and with it a separated sheet of mica, whose movement with the blade is insured by the projections on the under side of the latter.

We claim herein as our invention—

1. In a machine for separating the laminæ of mica, &c., the combination of a blade having a point and edges diverging from said point and operative to separate the laminæ 80 and means for holding the block to be separated in position for the entrance of the point of the blade between adjacent laminæ, substantially as set forth.

2. In a machine for separating the laminæ 85 of mica, &c., the combination of a revolving blade having an entering point and diverging operative edges, and means for holding the block to be separated in position for the entrance of the point of the blade between adjacent laminæ, substantially as set forth.

3. In a machine for separating the laminæ of mica, &c., the combination of a movable blade having an entering point and diverging operative edge, means for holding the 95 block to be separated in position for the entrance of the point of the blade between adjacent laminæ, and means for moving a separated lamina out of line with the block, substantially as set forth.

4. In a machine for separating the laminæ of mica, &c., the combination of a bed or table, a blade having an entering point and diverging operative edge movable over the surface of the bed or table, means for holding 105 a block of mica on said table for the entrance of the point of the blade between adjacent laminæ, and means for moving a separated lamina from under the block, substantially as set forth.

5. In a machine for separating the laminæ of mica, &c., the combination of a bed or table provided with an opening, a blade having an entering point and diverging operative edge movable along the surface of the table, 115 means for holding a block of mica on said table for the entrance of the point of the blade between adjacent laminæ, and means for moving a lamina when separated by the blade to such position that it will drop through 120 the opening in the table, substantially as set forth.

6. In a machine for separating the laminæ of mica, &c., the combination of a bed or table, a yielding presser for holding a block of 125 mica on the table, fingers for preventing the movement of the block along the table, and a blade movable along the surface of the bed or table, substantially as set forth.

7. In a machine for separating the laminæ of mica, &c., the combination of a bed or table, means for yieldingly holding a block of mica on the table, a blade movable along the surface of the table, and fingers vertically

movable by the blade for preventing the movement of the block along the table, substantially as set forth.

8. In a machine for separating the laminae of mica, &c., the combination of a movable blade provided on one side with grooves, means for holding a block of mica with its laminae parallel with the plane of movement of the blade and fingers for preventing the movement of the block with the blade, the ends of the fingers projecting into the grooves in the blade, substantially as set forth.

9. In a machine for separating the laminae of mica, &c., the combination of a blade, means for holding a block of mica with its laminae parallel with the sides of the blade, and means for forcing a separated lamina away from the blade, substantially as set forth.

10. In a machine for separating the laminae of mica, &c., the combination of a movable

blade, means for holding a block of mica with its laminae parallel with the plane of movement of the blade, means for causing a separated lamina to move with the blade and 25 springs for forcing such lamina away from the blade, substantially as set forth.

11. The method of subdividing pliable laminated mineral substances, such as mica, by the preliminary edgewise opening up or developing of the planes of lamination, followed by the action of a mechanically-driven blade operating in and along the developed planes of lamination, substantially as set forth.

In testimony whereof we have hereunto set 35 our hands.
